United States Patent Office.

RICHARD BUSH, OF BROOKLYN, NEW YORK.

Letters Patent No. 102,768, dated May 10, 1870.

IMPROVEMENT IN ROTARY PUMPS.

The Schedule referred to in these Letters Patent and making part of the same

To all whom it may concern:

Be it known that I, RICHARD BUSH, of the city of Brooklyn, Kings county, New York, have invented an Improvement in Centrifugal Pumps; and the following is declared to be a correct description thereof.

Centrifugal pumps have heretofore been made with radial buckets upon a cone that revolves within a case, the water being introduced at the apex of the cone, and centrally with the shaft, and thrown off by the centrifugal action into a circular delivery-passage.

I have discovered that the centrifugal action is more effective in drawing up the water and discharging it when the suction-pipe is placed as a tangent to the smaller portion of the cone of buckets, so that said pipe is at right angles, or nearly so, to the buckets as they come around successively; and I construct the induction or suction-pipe so that it may be placed to stand at any desired angle relatively to the discharge-pipe, thereby rendering the use of bends in the pipe superfluous under most circumstances. I also make the cone of buckets with a concave surface upon the cone at the base of the buckets, so as to give more space for the reception of the water near the middle part of the cone of buckets, and render the pump more efficient in its action.

In the drawing—

Figure 1 is a side view of the pump, and

Figure 2 is a section at the line xx .

The shaft a is to be mounted in any usual frame or bearings, and carries at one end the conical wheel of buckets, said wheel having the buckets b placed radially, as shown by dotted lines in fig. 1.

The surface of the cone c , to which the buckets b are connected, is not a straight line, but curved downward at e , so as to make the buckets wider at this point to give an increased hold upon the water.

The edges of the buckets b are straight, or nearly so.

The case containing the centrifugal wheel is made

of the two parts f and g , bolted together, and said case is made with a water-way, h , increasing in size and terminating in the discharge-pipe k .

The side of the case f is left open at the middle portion, and formed with an annular recess that receives the flange i of the induction-chamber l , and m is the induction or suction-pipe that enters one side of said chamber l , so as to be in a tangential position to the central portion of the cone of buckets, so that they will act with directness and efficiency in drawing the water into the wheel of buckets.

By the construction aforesaid, the pipe m and chamber l can be applied to the case f , so that the said pipe m may lead off in the most direct manner to the place from which the water is to be drawn.

The flange i , in the recess of the case f , allows the parts to be turned around, and, when in position, the flange i is to be secured to the case f by clamps o ; or other suitable means.

I claim as my invention—

1. The induction pipe m , placed in a tangential position to the buckets at their inner ends, in combination with the centrifugal wheel of buckets, cases f and g , and water-way h , substantially as specified.

2. The circular flange i around the induction water-chamber l , the induction-pipe m , connected to said chamber, the centrifugal wheel of buckets, b c , and the case f , arranged substantially as and for the purposes specified.

3. The conical wheel c of a centrifugal pump, made as a curve or concave at the base of the buckets b , and with the outer edges of the buckets straight, in combination with the inclosing-case and water-ways, substantially as and for the purposes specified.

Signed by me this 15th day of March, A. D. 1870,
RICHARD BUSH.
